N-SUBSTITUTED-3-AZABICYCLOOCTANES [3:3:0] AND SALTS THEREOF

Charles H. Grogan, Falls Church, Va., and Leonard M. Rice, Baltimore, Md., assignors to The Geschickter Fund for Medical Research, Inc., Washington, D.C., a corporation of New York

No Drawing. Filed Jan. 28, 1957, Ser. No. 636,511

11 Claims. (Cl. 260—247.5)

This invention relates to organic chemo-therapeutic agents and methods of their preparation, and more particularly relates to compounds of value in the treatment of cardio-vascular and other diseases. More specifically the invention relates to azabicyclooctane [3:3:0] bases, and the acid addition and mono- and bis-quaternary salts thereof.

It is a basic object of the present invention to provide novel organic compounds and methods for their preparation.

It is another object of the invention to provide novel, physiologically active compounds having chemotherapeutic or medicinal properties, particularly hypotensive activity.

It is a further object of the invention to provide novel compounds comprising N-dialkylaminoalkyl-3-azabicyclooctane [3:3:0] bases and N-heterocyclicaminoalkyl-3-azabicyclooctane [3:3:0] bases, and the acid addition, mono- and bis-quaternary salts of these bases and methods of synthesizing these compounds.

ods of synthesizing these compounds.

These and other objects and the manner in which they are accomplished will become apparent to those conversant with the art from the following description of the general class of compounds and certain specific examples of particular members as well as general and specific methods for their synthesis.

Generally stated, the novel compounds discovered are obtained by forming the N-dialkylaminoalkyl imides or N-heterocyclicamino alkyl imides from the anhydride of cis-1,2-cyclopentane dicarboxylic acid, the reduction of these imides by suitable means to obtain N-dialkylamino-alkyl-3-azabicyclooctane bases or N-heterocyclicamino-alkyl-3-azabicyclooctane bases which may be converted by appropriate means into the acid addition, mono- and bis-quaternary salts. Formula I shows the general structural formula of compounds obtained by the methods hereafter more particularly described.

and bisquaternary salts of

and bisquaternary salts of these bases are shown by Formulae 3(a) and 3(b) respectively.

FORMULA 2

Formula 3(a) Formula 3(b)

15 In these formulae A represents the azabicyclooctane nucleus and n a number from 1 to 6. R represents two alkyl groups with from 1 to 6 carbon atoms. R' represents an alkyl group with from 1 to 6 carbon atoms, an alkenyl group containing 3 to 6 carbon atoms such as the alkyl group or the structure $(N \equiv R)$ may represent a heterocyclic ring namely, morpholine, piperidine, pyrrolidine, piperazine or N -methyl piperazine, x^- represents an anion such as chloride, iodide, bromide, acetate, sulfate, hydrogen sulfate, methyl sulfate, toluene sulfate, 25 mucate, or theophyllinate. The site of both acid addition and quaternary salt formation on the nucleus A is always the ring nitrogen at position 3. In the quaternary salts R' may be the same as or different from R in any of the formulae given.

30 The free bases, Formula 1, and their acid addition salts, Formula 2, possess varying degrees of antihistaminic and bronchodilatory activity. The quaternary salts of these bases, Formulae 3(a), 3(b), and in particular the bisquaternary salts, Formula 3(b), possess 35 a marked hypotensive activity in mammals. For example the dimethiodide of Example I had a very favorable therapeutic ratio. At a total dosage level of 25 mg. I.M. there was a marked lowering of blood pressure and at the same time the toxicity has been determined 40 to be over 500 mg./kg.

In the process of preparing the bases of the invention, the imides used as starting materials may be prepared according to the process outlined in our copending application, Serial No. 634,469, now U.S. Patent No. 2,904,548, filed of even date herewith; wherein the N-dialkylaminoalkyl imides and heterocyclicaminoalkyl imides of 1,2-cis-cyclopentane dicarboxylic anhydride are described and claimed.

The following examples of specific compounds and methods will illustrate the manner in which the general synthesizing procedure may be applied to obtain particular members of the class of compounds discovered. It will be understood, however, that the following examples are merely illustrative and are not, nor are they intended to be, exhaustive of all the compounds embraced by the present invention.

Example 1.—*N*-dimethylaminoethyl-3-azabicyclo [3.3.0]octane, acid addition salts and quaternary salts

THE FREE BASE

24.5 grams of the dimethylaminoethyl imide of 1,2-ciscyclopentane dicarboxylic anhydride, dissolved in 200 ml. of anhydrous ether was added to a rapidly stirred solution of 15 g. of lithium aluminum hydride (LiAlH_4) in 600 ml. of anhydrous ethyl ether. Addition was made so as to just maintain reflux. The mixture was stirred for 2 hours after all the imide solution had been added.

This formula depicts the free bases, and for convenience in representation the azabicyclooctane nucleus (enclosed in parenthesis, Formula 1) will be designated by the letter A hereafter.

The acid addition salts of the bases illustrated by Formula 1 are shown by Formula 2 while the mono-

allowed to stand overnight and then decomposed by the dropwise addition of water so that reflux was just maintained. When the evolution of hydrogen had ceased, a slight excess of water was added, the mixture stirred 1-3 hours, inorganic material filtered off and the residue washed several times with ether. The ethereal filtrate was dried over anhydrous sodium sulfate, the ether stripped off and the residue vacuum distilled to yield 14 grams of colorless liquid with an amine-like odor, B.P. 93-95° C./10.0 mm.: $n_D^{20}=1.4755$

Analysis	Percent Carbon	Percent Hydrogen	Percent Nitrogen
Calculated.....	72.47	12.16	15.37
Found.....	72.41	12.32	15.43

THE DIHYDROCHLORIDE

The base was dissolved in anhydrous isopropanol and an excess of an alcoholic solution of HCl gas was added. On cooling and adding anhydrous ethyl ether, the dihydrochloride separated as crystalline white material with a melting point at 296-298° C.

THE DIMETHIODIDE

Ionic chloride.—Calculated—27.78%. Found—27.78%.

When the base was mixed with an excess of methyl iodide in anhydrous methanol and allowed to stand, the crystalline material crystallizing or precipitated out on adding anhydrous ether was generally a mixture of the mono- and di- methiodides. In order to obtain the dimethiodide free of monomethiodide, it was necessary to reflux the base with an excess of methyl iodide in anhydrous methanol 2-4 hours. The material that crystallized on cooling or on the addition of ether to the cooled reaction mixture melted at 235-238° C. On recrystallization from ethanol it melted at 236-237° C.

Ionic iodide.—Calculated—54.45%. Found—54.28%.

Example II.—*N-diethylaminooethyl-3-azabicyclo [3.3.0] octane, acid addition and quaternary salts*

THE FREE BASE

On reduction of the diethylaminoethyl imide with lithium aluminum hydride (LiAlH_4) in a manner similar to that described under Example I, 9 grams of the imide yielded 7 grams of the title base of Example II, with B.P. 59-63°/0.08 mm.: $n_D^{20}=1.4757$.

Analysis	Percent Carbon	Percent Hydrogen	Percent Nitrogen
Calculated.....	74.22	12.46	13.32
Found.....	74.55	12.16	12.94

THE DIHYDROCHLORIDE

Addition of an excess of a saturated solution of HCl in ethanol to the base dissolved in isopropanol, cooling and addition of ether produced the white crystalline dihydrochloride, M.P. 208-210° C. Recrystallization from isopropanol gave M.P. 210-211° C.

Ionic chloride.—Calculated—25.03%. Found—24.83%.

THE DIMETHIODIDE

The dimethiodide can be obtained directly by reacting the base with an excess of methyl iodide in acetone and allowing the mixture to stand 1 day. On refrigeration the dimethiodide separated in crystalline form, M.P. 213-215° C. with decomposition. Recrystallization from absolute ethanol sharpened the M.P. to 213-214° C. with decomposition. Decomposition may set in lower than the melting point if the material is heated very slowly.

Ionic iodide.—Calculated—51.35%. Found—51.11%.

Example III.—*N-dimethylaminopropyl-3-azabicyclo [3.3.0] octane, acid addition and quaternary salts*

THE FREE BASE

Reduction of 28 grams of the appropriate imide with 15 g. of lithium aluminum hydride (LiAlH_4) as detailed under Example I yielded 20 grams of the title base, B.P. 102-104° C./5.0 mm., $n_D^{20}=1.4742$.

10

Analysis	Percent Carbon	Percent Hydrogen	Percent Nitrogen
Calculated.....	73.41	12.32	14.27
Found.....	73.70	12.28	14.46

THE DIHYDROCHLORIDE

20 Addition of excess alcoholic-HCl to the base in isopropanol and precipitation with ether yielded the salt with M.P. 260-262° C. Recrystallization from isopropanol-ether gave M.P. 261-262° C.

Ionic chloride.—Calculated—26.33%. Found—26.20%.

25

THE DIMETHIODIDE

The dimethiodide formed readily with excess methyl iodide and the base in acetone at room temperature on standing 1 day, M.P. 255-256° C. Recrystallization 30 from isopropanol-ether gave M.P. 256-257° C.

Ionic iodide.—Calculated—52.85%. Found—52.97%.

Example IV.—*N-diethylaminopropyl-3-azabicyclo [3.3.0] octane, acid addition salts and quaternary salts*

35

THE FREE BASE

Reduction of the corresponding imide (10 grams) with lithium aluminum hydride (LiAlH_4) (6 grams) as detailed in Example I yielded 7.4 grams of the title base, 40 B.P. 99-103° C./1.2 mm., $n_D^{20}=1.4746$.

Analysis	Percent Carbon	Percent Hydrogen	Percent Nitrogen
Calculated.....	74.94	12.58	12.49
Found.....	74.92	12.48	12.54

THE DIHYDROCHLORIDE

50 This was formed analogous to Example III, M.P. 204-205° C. with no change on recrystallization from isopropanol-ether.

Ionic chloride.—Calculated—23.85%. Found—23.53%.

55

THE DIMETHIODIDE

This was also formed analogous to Example III, M.P. 201-203° C. Recrystallization from isopropanol-ether, M.P. 208-210° C.

Ionic iodide.—Calculated—49.94%. Found—49.88%.

60 *Example V*.—*N-morpholinopropyl-3-azabicyclo [3.3.0] octane, acid addition salts and quaternary salts*

THE FREE BASE

65 15 grams of the imide reduced with 6 grams of lithium aluminum hydride (LiAlH_4) as detailed under Example I, yielded 11 grams of the base, B.P. 94-98° C./0.1 mm., $n_D^{20}=1.4957$.

Analysis	Percent Carbon	Percent Hydrogen	Percent Nitrogen
Calculated.....	70.54	10.99	11.75
Found.....	70.74	11.01	11.99

UNITED STATES PATENT OFFICE
Certificate of Correction

Patent No. 2,962,496

November 29, 1960

Charles H. Grogan et al.

It is hereby certified that error appears in the above numbered patent requiring correction and that the said Letters Patent should read as corrected below.

Column 1, lines 53 to 58, the formula should appear as shown below instead of as in the patent:

column 2, line 20, for "alkyl" read —allyl—; line 62, for "ciscyclopentane" read —cis-cyclopentane—; column 3, line 24, strike out the heading "THE DIMETHIODIDE" and insert the same following lines 26 and 27; column 6, lines 15 to 20, the formula should appear as shown below instead of as in the patent:

Signed and sealed this 11th day of July 1961.

[SEAL]
